UNITED STATES PATENT OFFICE.

LESLIE CRANE, OF RUTLAND, VERMONT, ASSIGNEE OF ONE-HALF TO F. R. PATCH
MANUFACTURING COMPANY, OF RUTLAND, VERMONT, A CORPORATION OF
VERMONT.

ELECTRIC POLISHING MACHINE

Original application filed June 16, 1923, Serial No. 645,828. Divided and this application filed June 3, 1924. Serial No. 717,490.

This invention relates to certain new and useful improvements in electric polishing machines and more particularly to that type of machine in which a swinging arm is 5 mounted on a vertical standard carrying a polishing disc, and is a division of my application Serial Number 645,828, filed June 16, 1923, the object being to provide means for mounting the head.

10 A further object of the invention is to provide a polishing machine in which a central standard is mounted rigidly within a base and has mounted thereon a head carrying an electric motor.

15 A still further object of the invention is to provide a construction of polishing machine in which the working parts are enclosed so as to protect the same from grit and dust, thereby increasing the life of the 20 machine.

In the drawing I have shown a vertical section of my improved construction of standard for a polishing machine comprising a base (not shown) having an upwardly extending reinforced portion 2 having a tubular bore 3 into which is driven a tubular standard 4 and secured by pins 5 as clearly shown in the drawing. Driven into the top of the standard 4 is a socket 6 provided with a 25 shoulder 7 bearing on the upper end of the standard 4 as clearly shown. The socket 6 is annularly reduced as shown at 8 into which is secured a sleeve 9 forming with the socket 6 an annular chamber 10 into which is adapted to extend a tubular portion 11 of a head 12, said tubular portion being provided with 30 openings 13. The lower end of the tubular portion is mounted on ball bearings 14 within the bottom of the chamber 10 which is 35 adapted to receive a lubricant for keeping the bearings lubricated at all times.

Bolted to the head 12 is a collar 15 provided with an arm 16 adapted to support an electric motor. A collar 15 carries an arm 22 45 provided with a bearing 21 and a sleeve 23, which has its lower end arranged within a collar 24 having an annular extension 25 which extends into a cup 26 formed on the upper end of the extension of the base and in 50 which are arranged roller bearings 27, said collar having a hood 28 extending down over the cup portion for protecting the same. The collar 24 is provided with an arm 29 having a socket 30 at its outer end.

The construction thus far described forms 55 the main standard on which the head is revolubly mounted carrying the motor and driving shaft so that the swinging sectional arm of machines of this kind will swing around the standard and by forming the 60 standard hollow in the manner shown, the electric wires for the motor can be extended up through the base.

In machines of this character it is desirable 65 to form a construction in which the swinging frame can be rotated around a standard and as the weight is not equally distributed in view of the length of the sectional arm, it is desirable to provide means for taking care of the side thrust, which I have accomplished 70 and by the particular manner of mounting the parts, the machine is balanced.

The head 12, collar 15, sleeve 23 and collar 24 constitute what I have termed a body, 75 which is rovolubly mounted on the standard on ball bearings so that the same can swing around the standard freely, the sleeve 23 constituting a guide on which the tubular portion of the working arm is slidably mounted.

What I claim is:

1. In a polishing machine, the combination with a base having a vertical tubular standard fixed therein, of a socket arranged in the upper end of said standard having an annular shoulder resting on the upper edge of said standard, a sleeve fixed in said socket forming an annular chamber, a head having an apertured tubular portion extending into said chamber with its outer wall in contact with the outer wall of said chamber and ball bearings disposed in the bottom of said chamber upon which the lower end of said tubular portion of said head is mounted and a sleeve carried by said head extending downwardly 90 around said standard. 95

2. In a polishing machine, the combination with a fixed vertical tubular standard, of a socket having an annular reduced portion secured in the upper end of said standard, a sleeve secured in the reduced portion of said 100 socket forming an annular oil chamber, ball bearings disposed in the bottom of said chamber, a body surrounding said standard provided with a head having a depending tubular portion extending to said chamber and 105 mounted upon said bearings and a bearing carried by the standard for the lower end of said body.

3. In a polishing machine, the combination with a fixed vertical standard, of a socket secured in the upper end of said standard having an annular oil chamber, bearings disposed in the bottom of said chamber, a body provided with a head having a depending apertured tubular portion extending into said chamber and fitting the outer wall snugly thereof, the lower end of said tubular portion being mounted on the bearings within said chamber, said body being provided with a tubular portion surrounding said standard and a bearing carried by the standard for the lower end of the tubular portion of said body.
4. In a polishing machine, the combination

with a fixed vertical standard having an annular oil chamber at its upper end, a bearing arranged in the bottom of said chamber, of a body surrounding said standard having a head mounted on said standard and a downwardly extending apertured tubular portion carried by said head extending into said chamber having its lower end mounted on the bearings therein and having its outer wall in contact with the outer wall of said chamber and a bearing carried by the standard for the lower end of said body.

In testimony whereof I hereunto affix my signature.

LESLIE CRANE.
